MAIL CHUTES OF THE EXPOSED TYPE

James H. Hardie, Montreal, Quebec, Canada, assignor to The Canadian Cutler Mail Chute Company Limited, Montreal, Quebec, Canada

Application April 5, 1954, Serial No. 421,095

5 Claims. (Cl. 193—8)

This invention relates to improvements in mail chute assemblies for conveying letters from the top and intermediate floors of a building to a mail box located at the bottom or ground floor, and particularly to the exposed type of chute which projects forwardly from a wall surface.

Mail chutes are usually built in sections of one to a floor of a building, which, when interconnected, one to another, combine to form a unit assembly providing a continuous conveying channel from the top to the bottom floor of a building. Heretofore, it has been the practice to prefabricate each floor section as a plurality of sub-sections, including upper and lower chute channel members, a ceiling connection chute and a floor connection chute, which had to be assembled on the job, requiring considerable time and skill to adjust and fit these sub-sections together into a floor section. Then too, the interconnecting of these sub-sections necessitated the provision of a plurality of expensive connection units required to reinforce the sub-sections at their joints and to give protection against tampering with the chute. As an example, a section having the number of sub-sections outlined above, requires a specially constructed ceiling collar, a neck moulding about the juncture of the ceiling connection chute and the upper channel member, an intermediate supporting frame about the juncture of the upper and lower channel members and separately formed base and sub-base units between the lower channel member and the adjacent floor level. All of these units, being disposed about the chute in an exposed condition, must be processed to provide an attractive appearance. This calls for additional expense both in materials and labour to produce these units as a finished product.

The general object of the present invention is to provide a mail chute assembly which comprises a plurality of unit sections of novel construction which eliminates the separate prefabrication of a substantial number of sub-sections and complementary connection units and their assembly as floor sections of an assembly unit.

A particular feature of this invention consists in the provision of floor section units each comprising a single, full-length chute channel member extending between a ceiling and a floor therebelow and a floor connection chute for direct interconnection of the channel member with an adjacent floor section channel member.

A further object is to provide a full-length channel member having a novel side-wall construction comprising a double-walled forward extension and shoulder arrangement for the retention therebetween of front closure members along the length of the channel member.

Another object is to provide a novel front closure arrangement for the open face of a full-length channel member in which certain of the closure members are removably interfitted between the sides of the channel member in a novel manner which prevents their removal by unauthorized persons.

Still another object is to provide a front closure ar-

2

angement of the character described with novel interlocking elements.

A still further object is to provide a novel hanger for the support of a floor connection chute in the chute assembly.

Certain other features of my invention afford advantages over the conventional chute assembly not hitherto contemplated. For example, the provision of a fixed cover above the removable front closures between the side walls of the chute channel affords an inexpensive continuity to the front closure. A slide plate is also mounted rearwardly of this cover in an inexpensive but effective manner to provide a suitable baffle which directs descending mail toward the centre of the chute passageway. This baffle feature is also to be found in the novel arrangement of the fixed front closure located beneath the removable closure panels.

The above and other objects and features characteristic of this invention will be understood more readily from the following detailed description taken in connection with the accompanying drawing, in which—

Fig. 1 is a front elevational view of a chute assembly embodying my invention.

Fig. 2 is a sectional view, enlarged, of the lower portion of the assembly taken along the section lines 2—2 of Fig. 1.

Fig. 2A is a sectional view of the upper portion of the assembly taken along the lines 2a—2a of Fig. 1, and being, in effect, a continuation of Fig. 2 at points A—A.

Fig. 3 is an enlarged sectional view taken along the lines 3—3 of Fig. 1.

Fig. 4 is an enlarged sectional view taken along the lines 4—4 of Fig. 1.

Fig. 5 is an enlarged sectional view taken along the lines 5—5 of Fig. 1.

Fig. 6 is an enlarged sectional view taken along the lines 6—6 of Fig. 1.

Fig. 7 is a sectional view taken along the lines 7—7 of Fig. 6.

Fig. 8 is a sectional view taken along the lines 8—8 of Fig. 6.

Fig. 9 is a sectional view taken along the lines 9—9 of Fig. 2A.

Fig. 10 is a sectional view taken along the lines 10—10 of Fig. 1.

Fig. 11 is a fragmentary view in elevation of the mail pocket shown at 10—10 in Fig. 1, parts being broken away to show certain details.

Fig. 12 is a sectional view taken along the lines 12—12 of Fig. 11.

Fig. 13 is a fragmentary detail view in elevation of a floor connection member shown in Figs. 2 and 2A.

Fig. 14 is a plan view of the floor connection member shown in Fig. 13.

Fig. 15 is a sectional view taken along the lines 15—15 of Fig. 1.

Fig. 16 is a detail view of a fragment of the lower tapered end of the channel member shown in Figs. 2 and 2A.

Referring more particularly to the drawings, 5 generally designates a mail chute assembly which is secured along the length of a pair of spaced, parallel, vertically disposed angle beams 6. Beams 6 each have one flange 7 partially embedded in a wall or partition structure 4 so that sections of the remaining flange 8 between each floor level and the ceiling thereabove, are inwardly directed and are parallel to the finished wall surface. The chute assembly includes a sheet metal chute channel member 9 extending intermediate each floor level 10 and a ceiling level 11 thereabove, a rectangular thimble 12 extending through each floor structure, and a floor connection member 14 extending through thimble 12 to cooperate with

adjacent ends of two successive channel members 9 in forming a continuous passageway for mail delivery to a suitable receptacle at the base of the assembly.

Channel member 9 is formed from sheet metal which is shaped to provide an inner wall 15 between two forwardly extending side walls 16. Forward marginal portions of said side walls 16 are bent inwardly upon themselves to provide double-walled, front marginal projections 17 and then at right angles a short distance from the front edge to provide inwardly projecting shoulders 18. Shoulders 18 form seats for the rearward support of upper and lower removable front closure members 20 and 21 when they are confined between the marginal projections 17 of the channel member 9.

The upper end of each channel member 9 terminates slightly below a ceiling level 11 and is secured to a cross-plate 22 which is fastened to the rear of the inwardly directed flanges 8 of angle beams 6 by bolts 23. A transverse spacer bar 24 extends between the marginal edges of flanges 8 and intermediate the inner wall 15 and cross-plate 22 so that bolts 25, extending through wall 15, spacer bar 24 and cross-plate 22, secure the channel member 9 with the outer surface of wall 15 in abutting engagement with the opposing surfaces of flanges 8.

The lower end of chute channel member 9 terminates a substantial distance above the floor level 10 and is secured in a similar manner by bolts 26 to a second cross-plate 27 which is fastened to the rear of flanges 8. Bolts 26, extending through wall 15, a spacer bar 29 and cross-plate 27, likewise secure the channel member 9 with the outer surface of wall 15 in abutting engagement with the opposing surfaces of flanges 8.

The open face of channel member 9 is provided at its upper end with a cover plate 30 having rearwardly directed side flanges 31 disposed to lie between the forward marginal projections 17. A slide plate 32 having forwardly directed side flanges 33 is located inwardly of cover plate 30 with its side flanges 33 wedged between the double walls of the forward marginal projections 17 of channel member 9. The side flanges 33 of slide plate 32 flare from top to bottom so as to provide the plate portion 32 with a downwardly and inwardly inclination. Plate 32 has its upper marginal portion bent to provide a flange 34 which is hooked over the upper edges of shoulders 18. Bolts 35, extending through forward marginal portions 17 of the channel member side walls, secure the upper ends of the cover plate 30 and slide plate 32. The lower end of cover plate 30 has a pair of angle plates secured to the inner surface thereof so that the free end of the plates may be bent outwardly and around the adjacent shoulder 18 to provide a retaining clip 36 for the lower end of said cover plate. A channel-shaped collar, comprising partially telescoped upper and lower channel-shaped plate members 37 and 38 secured in nested relation, is fitted about the front and sides of the upper portion of chute member 9 so that the upper channel-shaped plate 37 reaches the ceiling level 11 to close the gap between the upper end of chute member 9. The lower channel-shaped plate overlies and is secured to cover plate 30 by bolts 39.

The lower portions of the inner and side walls 15 and 16 of channel member 9 have inwardly tapered extensions 15a and 16a respectively, the lower ends of which terminate a substantial distance above the floor level. The double-walled projections 17 and shoulders 18 terminate at the point where the side walls 15 begin to taper, thus providing the side wall extensions 16a with marginal portions 40 of single ply below the double-walled portions 17. A guide plate 41 having forwardly directed flanges 42 is secured across the front of the lower tapered extension by means of the flanges 42 which are welded to marginal portions 40 of side wall extensions 16a so as to provide a downward and inward inclination to plate 41.

The tapering extension of channel member 9 is received

within the upper end of a four-sided, elongated, tapering floor connection member 14 which projects through thimble 12 and into the upper end of a second channel member 9 located between the floor and ceiling of a lower level. Floor connection 14 has its rear wall 45 elongated at the upper end to provide an extension member 46, the upper marginal portion of which is bent outwardly and downwardly to overlie a transverse stiffening plate 47. The floor connection 14 is hung from the cross-plate 27 carried by beams 6 by means of bolts 48 which extend through openings in member 46 and plate 47, the latter being disposed between the opposing edges of the flanges 8 of said beams.

The lower end of channel member 9 and the floor connection 14 above the floor level are enclosed by a base 50 which is formed from a single sheet or slab of material to provide vertical front and side walls. Base 50 surrounds the front and sides and is secured in place by spot welding upper marginal portions of its side walls to portions of the channel member side walls 16 adjacent the tapering extensions 16a.

The upper front closure member 20, which comprises a plate glass panel 55 in a frame including the hollow sheet metal side mouldings 56 and top and bottom connecting rails 57 and 58, is fitted between the forward marginal projections 17 of chute member 9 to bear against the seat forming shoulders 18. The top rail 57 is angle-shaped, having one flange disposed to lie across the outer face of panel 55 and the other flange projecting forwardly from the lower edge of said first flange. The upper marginal portion of closure member 20 is inserted between the lower ends of cover plate 30 and slide plate 32 so that the forwardly projecting flange of top rail 57 underlies the lower edge of cover plate 30.

Bottom rail 58 of upper closure member 20 is supported on a locking band bracket 60 which is secured between the marginal projections 17 by screws 61 at a point which prevents removal of member 20 when a locking band 62 is emplaced about the bracket 60. Bracket 60 has a rear wall 63, the front face of which is vertically disposed and the rear face of which is downwardly and outwardly inclined. Side walls 65 project forwardly of rear wall 63. These side walls have inwardly directed thickened portions 66 from which pins 67 project forwardly of the front face of said side walls. Bracket 60 is secured between the marginal projections 17 with the seat forming shoulders 18 extending into vertical slots 68 in the ends of rear wall 63 so that the side walls 65 afford support to the upper closure member 20 by direct contact with adjacent ends of bottom rail 58. Inwardly directed locking tongues 69 are provided on the front face of rear wall 63 at the central portion thereof to be engaged by a suitable locking mechanism which projects rearwardly from the locking band 62.

The lower closure member 21, which comprises a plate glass panel 70 in a frame including hollow sheet metal side mouldings 71 and top and bottom connecting rails 72 and 73, is fitted between the forward marginal projections 17 of channel member 9 to bear against shoulders 18. The bottom connecting rail 73 extends across the lower front face of panel 70 and is provided with a rearwardly offset flange 74 at its lower end which underlies the lower edge of the panel 70. A second offset flange 75 projects forwardly from the upper end of the rail 73. When the closure member 21 is inserted in the lower half of channel member 9, offset flange 75 is supported on the upper edge of the front wall of base 50 and on clips 76 secured to the inner face of the base front wall at the upper end thereof. Clips 76 also serve to hold the lower end of the closure member 21 against shoulders 18 to ensure that the rear face of the closure member will be rearwardly offset with respect to the upper edge of inclined guide plate 41.

The top connecting rail 72 is provided with legs 77 which project into the upper ends of hollow side mould-

ings 71 and are secured to the side mouldings by screws 78. The lower portion of locking band 62 is secured to the front face of top rail 72 by screws 79 so that, when the lower closure member 21 has its upper end seated against shoulder 18, the upper portion of locking band 62 overlaps locking band bracket 60. The inner face of locking band 62 is provided at each end with pin receiving holes 80 adapted to receive the pins 67 carried by bracket 60. The interfitting of pins 67 in holes 80 ensures a proper centering of the locking band 62 so that a suitable locking mechanism carried by band 62, will releasably engage the locking tongues 69 on the front face of the locking band bracket 60 to thereby secure both the upper and lower front closure members 20 and 21 against unauthorized removal.

The lower closure member 21 is also provided with a mail pocket 85. Pocket 85 comprises a front wall 86 and side, top and bottom walls 87, 88 and 89 extending rearwardly from said front wall. The side walls 87 are each provided with a laterally extending marginal flange 90 each having top and bottom bracket extensions 91. Top wall 88 is provided with an elongated, letter-receiving opening 92. And bottom wall 89 has a depending marginal flange 93. In order to insert the pocket in the lower closure, the glass panel 70 is divided into vertically spaced upper and lower sections. The pocket 85 is disposed between the vertically spaced sections of panel 70 with the lateral flange 90 and bracket extensions 91 received in the hollow moulding strips 71 and resting on the upper edge of the glass panel lower section so that the depending flange 93 of bottom wall 89 overlaps the front face of said lower section of the glass panel. Bracket extensions 91 are secured to the moulding strips 71 by screws, as indicated at 94. The rear face of top wall 88 and side walls 87 are recessed, as indicated at 95, to receive a transverse plate 96 having its upper marginal portion bent forwardly and then upwardly, as indicated at 97, to provide a supporting rail for the lower edge of the upper section of glass panel 70. Screws 98 secure the plate 96 to the rear face of the mail pocket.

A pair of closure plates 100 and 101 are pivotally mounted to swing about a common axis 102 adjacent the upper end of the mail pocket 85. Plate 100 serves to close off the opening 92 in the pocket top wall and plate 101 serves to close the passageway defined by the chute channel member 9. It will be seen that the lower end of plate 101 overlaps the rear marginal portions of the pocket wall 89 and the upper edge of the glass panel lower section to provide a baffle for directing descending mail into the chute passageway. Plate 101 may be secured in its open position by any fastening means, for example, by a screw 103 which engages a boss 104 on the inner surface of the mail pocket front wall 86.

The chute assembly as above described provides a compact and greatly simplified arrangement of elements as compared with the conventional types of chutes. Previously a mail chute assembly comprised separate component elements including separately formed upper and lower chute channel members between the ceiling and floor below, a separately formed ceiling connection chute between the ceiling and the upper channel member, a thimble between floors, and a floor connection member between the ceiling connection chute and a lower channel member located thereabove. In addition, this called for a special ceiling collar unit adapted to enclose the lower projection of the thimble and the upper end of the ceiling connection chute, a neck moulding about the connecting portions of the ceiling connection chute and the upper channel section, an intermediate supporting frame for the upper and lower channel member connection, and a base and sub-base frame mounted one upon the other to encompass those portions of the thimble and floor connection member extending above the floor, as well as the interfitting portions of the lower channel member and the floor connection.

The present invention eliminates separate upper and lower channel members and a ceiling connection chute by the provision of a single full-length channel member so that a superimposed floor connection member has its lower end projecting into the upper end of the channel member. This arrangement also eliminates the necessity of the type of ceiling collar used and of a neck moulding and an intermediate supporting frame about the channel member. The formed sheet metal base enclosure, according to the present invention, also greatly simplifies the base construction as well as reducing the cost, both in material and labour, of enclosing the base portion of a chute assembly adjacent each floor level as compared with the conventional base unit and the sub-base unit mounted thereon, each requiring separate installation to complete the assembly.

The chute channel member 9, in addition to being a one-piece unit, presents certain other novel features. The novel formation of the double-walled forward projections 17 and the shoulders 18 from marginal portions of the channel side walls affords a reinforced side enclosure for the front closure members 20 and 21 as well as a seating for same. The upward extension of the channel member provides a means for supporting a cover and slide plate assembly which is arranged between the forward portion of the channel member in a novel manner substantially as an extension of the upper closure member 20.

Although I have described and illustrated what are now believed to be the preferred embodiments of this invention, it will be appreciated that modifications and changes may be resorted to without departing from the scope and spirit of this invention as defined in the appended claims.

What I claim is:

- 35 1. A mail chute assembly comprising a plurality of floor chute sections arranged in connected superimposed relation, each section including a single, sheet metal chute channel member projecting from a wall surface and extending substantially the full length between a ceiling and a floor below, said chute channel member including a rear wall and side walls extending forwardly from said rear wall, a plurality of front closure members supported along the length of the open face of said single chute channel member between forward portions of its side walls and a floor connection member projecting through a flooring and having one end fitted about the lower end of said single channel member and the other end projecting into the upper end of a second floor section channel member therebelow to provide an uninterrupted chute passage throughout the length of said chute assembly, one of said front closure members comprising a lower closure plate extending across the open face of said channel member adjacent the lower end thereof and below the remaining front closure members, said lower closure plate being provided with side flanges located adjacent the upper end of said plate, said side flanges being directed forwardly of the closure plate and being secured to the inner surface of the channel side wall so as to provide said lower plate with a downward and inward inclination.
- 40 2. A mail chute assembly comprising a plurality of floor chute sections arranged in connected superimposed relation, each floor section including a single, sheet metal chute channel member projecting from a wall surface and extending substantially the full length between a ceiling and a floor below, said chute channel member including a rear wall and side walls extending forwardly from said rear wall, a plurality of front closure members supported along the length of the open face of said chute channel member between forward portions of its side walls, a floor connection member projecting through a flooring and having one end fitted about the lower end of said chute channel member and the other end projecting into the upper end of a second floor section channel member therebelow to provide an uninterrupted chute
- 45
- 50
- 55
- 60
- 65
- 70
- 75

passage throughout the length of said chute assembly, and laterally spaced vertical angle beams each having one flange rearwardly directed and embedded in said wall and the other flange inwardly directed with its front face spaced outwardly from and substantially parallel to the plane of the finished wall surface, a plurality of cross-plates spaced at vertical intervals between said angle beams and secured to the rear face of said second mentioned angle beam flanges, and means securing said single channel member to at least one of said cross-plates so that marginal portions throughout the length of the rear wall of said single channel member flatly engage the front faces of said second mentioned angle beam flanges.

3. A mail chute assembly as set forth in claim 2, including spacer bars extending between the marginal edges of said second flanges of the angle beams, said spacer bars being also disposed between said cross-plates and the rear wall of said channel member and being of a thickness equal to the thickness of said second flanges of the angle beams to provide a continuous support across the width of said channel rear wall in the region of said spacer bars.

4. In a mail chute assembly, including vertical angle beams having one flange embedded in a wall structure and the other flange spaced outwardly from and parallel to said wall surface, a single sheet metal chute channel member vertically arranged to extend substantially the full length of the wall intermediate a ceiling and a floor therebelow, said channel presenting a rear wall and side walls extending forwardly of said rear wall, means for securing said channel member to said angle beams so that substantially the full length of the rear wall of said channel member flatly engages the front faces of said other flanges of the angle beams, said chan-

nel side walls having forward marginal portions folded inwardly upon the side walls to provide double-walled, forward marginal projections and then at right-angles to the side walls to provide inwardly projecting shoulders along the length of said channel member, upper and lower front closure panels receivable in the open face of said channel member between said double-walled projections and in pressure contact with said shoulders, a bracket member secured between the forward marginal projections of the sides of said channel member for vertical support of said upper front closure panel, said bracket presenting a transverse rear wall provided with slots in opposite ends into which said channel side wall shoulders are received and having locking tongues on the front face thereof and side walls projecting forwardly from opposite ends of the transverse rear wall of said bracket member between the double-walled, marginal projections of the channel member side walls, and a locking band butted against the forward edges of the bracket side walls and releasably secured to said transverse member by engagement with said locking tongues.

5. A mail chute assembly as set forth in claim 4, including centering means for said bracket and said locking band, the one carrying projecting members receivable in complementary recesses in the opposing surface of the other.
